UNITED STATES PATENT OFFICE.

ROBERT E. NELSON, JR., OF COLUMBIA, VIRGINIA.

ELECTRIC CASH-REGISTER SYSTEM.

SPECIFICATION forming part of Letters Patent No. 449,249, dated March 31, 1891.

Application filed August 21, 1890. Serial No. 362,652. (No model.)

To all whom it may concern:

Be it known that I, ROBERT E. NELSON, Jr., of Columbia, county of Fluvanna, and State of Virginia, have invented a new and useful 5 Improvement in Electric Cash-Register Systems; and I do hereby declare that the following is a full, clear, and exact description of the invention, which will enable others skilled in the art to which it appertains to make and 10 use it, reference being had to the accompanying drawings, forming a part thereof.

My invention relates to an improvement in electric cash-register systems; and it consists in a novel combination of one or more local 15 cash registers and indicators situated at different points in a store and a central register at a distant point, whereby the value of each sale made is registered and indicated on the individual machines and is added or registered 20 on a central register, so that at all times the central register will show the sum total of all sales made in the store.

The object of my invention is to provide a system whereby upon the depression of two 25 or more keys simultaneously in the same machine or on different machines the full value of said keys will first be added on the central register, and will then be added on their individual registers in their respective local 30 machines, at the same time indicating on said local machines the values of the purchases made.

It also consists in combining with the local machines and said central register one or 35 more registers located at the proprietor's house or other points, so that it may be known upon inspection of said registers at any time just what amount of sales have been registered in local machines up to the time of such 40 inspection.

It also consists in a novel combination and arrangements of parts hereinafter described, and pointed out in the claims.

In the accompanying drawings, Figure 1 is 45 a diagrammatic plan view of a central register and two local cash-registering machines connected therewith in electric circuit. Fig. 2 is a diagrammatic plan showing the local machines connected with the central register. 50 Fig. 3 is a diagrammatic sectional view illustrating the mechanism in the central register and in one of the cash-registering machines

connected therewith in electric circuit. Fig. 4 is partly a top plan view and partly a section showing the arrangement of the prime-moving series of summation-gears, the electric actuating devices, and the indicating-disk-operating mechanism of one of the local cash-registering machines.

The cash-registering machine which I prefer to use in my improved electric system is of my own invention, and is made the subject of a separate application for Letters Patent of the United States filed August 15, 1890, Serial No. 362,061; but the following is a brief 65 general description of the machine which I prefer to use, although I would have it understood that I do not confine myself to the use of this type of connected summation-gears in my improved electric system, as any suitable 70 cash-registering mechanism may be employed with equal facility in connection with my cash-registering system.

a a' are the prime-moving gears, mounted loosely on a fixed longitudinal shaft D, and *a² a³* are the escapement-wheels, also mounted loosely on said shaft, each of the gear-wheels *a a'* having an orbital wheel *a⁴*, which have their teeth meshing with the spur-gear teeth on the pairs of escapement-wheels. The pairs 80 of wheels, the intermediate gears, and the orbital wheels constitute the primary summation-gear.

The secondary summation-gear is mounted on a fixed shaft E, which is parallel with the 85 shaft D, and said secondary summation-gear consists of a series of pinions *b b'*, which mesh with the gears *a a'* on shaft D, a series of gears *b² b³*, loosely mounted on said shaft E in pairs and connected each to the proximate pinions *b b'* by a sleeve, and gears *b⁴*, arranged between the pairs of gears, and each of said gears *b⁴* having an orbital wheel *b⁵*, which engages the respective pairs of gears *b² b³*.

The tertiary summation-gear is loosely mounted on a rigid shaft F, arranged parallel with the shaft E, and said tertiary summation-gear comprises two pairs of gears *c c'* *c c'*, between each pair of which gears are 90 loosely mounted the gears *c² c³*, respectively, which carry orbital wheels *c⁴*, that mesh with the pairs of gears *c c'*. A series of pinions *c⁵* are loosely fitted on the shaft F and mesh

with the gears b^4 on the shaft E, and the pinions c^5 are connected to the proximate members $c\ c'$ of the pairs of gears by means of sleeves, as shown in Fig. 4.

5 The quartenary summation-gear consists of a pair of gears $d\ d'$, mounted on a rigid parallel shaft G, and between said gears $d\ d'$ is a gear d^2 , having an orbital wheel d^3 , which engages said pairs of gears $d\ d'$. A sleeve connects the gear d' with a pinion e , that engages the gear c^8 , and on said sleeve is a miter-gear e' , having also spur-gear teeth. A similar sleeve connects the gear d' with a pinion e^2 , which engages the other gear c^2 , 15 and on this sleeve is a miter-gear e^3 , having also spur-gear teeth. A pair of horizontal shafts H I are arranged at right angles to the shaft G, and they are geared to the miter or bevel wheels $e'\ e^3$, said shafts carrying the dollars and cents disks $k\ l$, the two shafts being geared together at h and having weights and cords h' for turning the indicator-disks to zero. I also provide a weight and cord J, which is connected to the shaft F, (or a spring 20 device may be used,) and which tends to turn all of the intermeshing summation-gears and to turn all the escapement-wheels $a^2\ a^3$ in the direction indicated by the arrow in Fig. 3.

Two disks $k\ l$, for indicating the dollars 30 and cents, are provided for each of the cash-registering machines, and these disks are arranged to turn automatically to indicate the value or sum of the values of the key or keys operated in the local machine when 35 a sale is made, and automatic devices for operating said disks are connected to a bar n , arranged under the finger-keys f , presently referred to, said automatic devices consisting of the fixed clutches R on the shafts H I, 40 the sliding clutches S, also fitted on said shafts and arranged to engage with the fixed clutches, the weighted cords h' , the endless strap T, engaging the sliding clutches S, the upright lever Y for operating the endless strap, 45 and the sliding rod X, connected to the bar n by a link, which bar is adapted to arrest the downward movement of the finger-keys f until the indicator-disks are reset to zero. I also provide a suitable registering mechanism, arranged above the shaft G and gearing with the spur gear-wheels on the miter-gears $e'\ e^3$, 50 which registering mechanism may be of any suitable preferred construction, and the said registering mechanism is connected to the prime-moving gears a by the intermediate gearing, as shown.

This general description of my cash-registering machine is deemed sufficient for the purposes of this specification, and reference 60 is made to my other application for a detailed description of the preferred form of registering-machine.

The series of finger-keys f do not actuate the prime-moving gears directly, but form 65 merely circuit-closers for electric contacts $1'\ 2'\ 3'\ 4'$, Figs. 1 and 3. The contacts $1'$ and $3'$ are included in the electric circuit 11, and

contacts $2'\ 4'$ are included in the electric circuit 22, as shown in Fig. 1. Retractile springs e^7 normally raise the finger-keys and cause them to keep the contacts $1'\ 2'$ normally closed.

Mounted on independent supports are a series of pivoted escapement-pallets f' , of which there is one for each escapement-wheel, and the said escapement-pallets are provided with suitable springs, (not shown,) which keep the upper teeth of said pallets normally in engagement with the escapement-wheels, and hence the prime-moving gears are normally at rest. The arm of each escapement-pallet is provided on its lower side with a suitable armature g , adapted to be attracted by its respective electro-magnet h^2 , there being one of said electro-magnets for each of the escapement-pallets, and the said electro-magnets being included in the circuits 22, which are normally broken at $4'$.

In each local cash-registering machine I employ a locking device o for locking the drawer when closed and an electro-magnet r to actuate the locking device and unlock the drawer, and I also employ a suitable electric bell s in each local cash-register machine connected with the magnet r by the conductor t . 95 From this construction it will be apparent that upon the depression of a key the bar n will also be depressed a short distance, which will cause the bar X to be pushed toward the indicators $k\ l$ and the vertical lever or bar Y to be turned on its pivot. This movement of the lever or bar Y through the strap T and clutches S and R disconnects the indicators from the escapement mechanism and allows them, through the weighted cords h' , to return to zero. In the meantime the spring-pressed and pivoted lug r on the reciprocating bar R', which is attached to the bar or lever Y, strikes the flange r^2 on the clutch R and arrests the motions of all the parts, including the bar n and the key, until a cut-away portion r^3 on said flange r^2 comes opposite said lug, when said lug r passes through said cut-away portion, and the end of the lever or bar Y becomes disengaged from strap T. As soon as 105 this takes place the clutch S becomes again engaged with the clutch R by means of a spring, and the key continues to descend, closing the circuit with the central register, which in its turn closes a circuit through a local register and causes both said register and its indicator to be actuated, all as will appear more fully hereinafter. The cut-away portion on the flange of the clutch R is so positioned that the lug only passes it when the indicators are at zero. Hence the bar n and the keys are arrested in their downward motion until said indicators are reset to zero, 110 after which the keys may continue to descend. All the parts will automatically return to the position shown in Fig. 3, owing to the spring-pressed and pivoted lugs with which the ends of the bar Y and the reciprocating bar are provided, and which will swing on their piv-

115 120 125 130

ots only as the bars are returned. This mechanism is not specifically claimed in this application and is more fully set forth in my other pending case referred to.

5 The central register is provided with a registering mechanism f' , prime-moving escapement-wheels f^3 , intermediate gears connecting the prime-moving wheels with the registering mechanism, and the prime-moving 10 wheels are positively turned by a suitable cord and weight or spring mechanism, such as is employed in the local cash-registering machines, hereinbefore described.

15 Each escapement-wheel f^2 of the central register has its respective escapement-pallet f^2 , which normally keeps the escapement from turning, and is adapted to be attracted by its respective electro-magnet h^3 to enable the escapement-wheel to turn through the space of 20 one of its teeth when a finger-key of one of the local machines is operated in the manner to be presently described.

25 From the foregoing it will appear that the keys exert no force when operated, but similarly momentarilly release the escapement-wheels of the local machines and the central register and permit the cord and weight or spring devices before referred to to turn the said wheels.

30 In Fig. 1, A represents the electric battery, from the negative pole of which extends a conductor B. A conductor C extends from the positive pole of the battery A, and the wires of the circuits 2 2 are attached to the 35 conductors B C, which circuits 2 2 are adapted to be closed by the fingers f at $4'$, of like value in all of the local machines Nos. 1, 2, 3, &c., which are connected with or included in the system. The open circuits 1 1 are connected 40 to the poles of the battery A, and the said circuits are adapted to be closed by the finger-keys of like value in each of the local machines in the system at the contacts 3'.

45 The circuits t t , in which are included the bell and electric locking devices of the various local machines, are independently connected to the positive and negative poles of the battery.

50 The electro-magnets h^3 in the central register are connected to the negative conductor B, and are in the circuits 1 1 controlled by finger-keys of like value in the local machines through the contacts 3', which are connected at their terminals to the circuits 1 55 1 at xx . The electro-magnets h^2 , of like value, in the local machines are included in the circuits formed by wires 4, which wires 4 connect at one terminal with contacts 4'. The escapement-pallets f^2 of the central register 60 are connected, respectively, to the negative pole of the battery, as at W, and constitute shunt-switches, as will presently appear.

65 In Fig. 1 I have displayed the various circuits at large, illustrating two prime-moving connections or escapements of the central register and of two local machines connected in circuit therewith in order that the various

circuits may be readily traced and the operation of the system made clear; but in practice the various conducting-wires will be 70 arranged in cables, as shown in Figs. 2, 3, and 4.

The operation of my electric cash-register system is as follows: It will be seen that all magnets, both in the central register and in the local machines, are joined in parallel arc, except the bell-ringing and drawer-releasing magnets, which are in series, so that normally no current flows through the system. Upon the depression of any key in machine No. 1 80 contacts 3' and 4' will be closed, and the current will flow from the positive pole through wire 1, through contact 3', through wire 1, magnet h^3 , conductor B and back to battery. Magnet h^3 , being energized, will close circuit 85 at z . The current now flows through wire C, the conductors 2 and 4, the contact 4', through the magnet h^2 , the wire 2, the escapement-armature f' , and back to the battery. The magnet h^2 , being energized, operates to close 90 at contacts z' the circuit 5 5, which is joined to circuit t t , as shown in Fig. 3, and the current flows from the positive pole of the battery through the conductor t , bell-ringing magnet s , drawer-releasing magnet r , conductor 95 5, contact z' , escapement-armature of magnet h^2 , and the conductors 5 and t back to the battery, so that upon the depression of said key the escapement in the central register of same value as said key is first operated, and 100 then the escapement of the same value as said key in the local machine is operated, registering the value of said key in succession at each place and ringing the bell and releasing the drawer after the registration has taken place 105 in both machines. At the same time the value of the key depressed is indicated on the local machine through the transmitting mechanism or summation-gears heretofore referred to.

If two or more keys in the same machine are 110 depressed simultaneously, each operating separate escapements in the central register through independent circuits, their full value will be added on said register, as will also their 115 full value be added and indicated on their local machines, since the escapement mechanism in both cases is constructed as in my application aforesaid. In Fig. 1 I have shown the keys of the same value in both machine No. 1 and machine No. 2 as operating the 120 same escapement f' in the central register, and it is evident that if both keys should operate this escapement simultaneously only the value of one of such keys would be registered. I overcome this objection in two ways: 125 first, by employing a separate escapement f' for each key of the same value in the different machines used, so that each of said keys and said escapements f' are included in their own individual circuits; second, by employing 130 a cut-out device by means of which when both keys are in the same circuit with said escapement f' one of the keys will be cut out while the other is registering. This cut-out

device is shown in Fig. 1. Springs normally hold the keys against the upper contacts 1' 2', as shown, and if the key in machine No. 2 should be depressed while the corresponding key in machine No. 1 is not depressed the current will flow through wire 1, contact 1' in machine No. 1, and down to machine No. 2, contact 3' in said machine, through wire 1, magnet h' , and back to battery, as before. Contact z is closed and the current flows through wires C and the wire 2, the contact 2' in machine No. 1, the wires 2 and 4, the contact 4', the magnet h^2 , and the wire 4 in machine No. 2, the wire 2, contact z , armature f' , and back to battery, as before. The circuit is also made through contact z' of machine No. 2, wire t , bell, and drawer-releasing magnet, as before, so that so long as key in machine No. 1 is raised the value of the key in machine No. 2 will be registered on the central register and indicated and registered on its local register, as in the first case; but if while the key in machine No. 2 is depressed I also depress a key of the same value in machine No. 1, contacts 1' 2' will be broken in machine No. 1, and no registration from machine No. 2 can take place, machine No. 1 only actuating the central register. In this case the operator at machine No. 2 will continue to hold his key until he hears the bell ring in his machine, when he knows that the key in machine No. 1 has been raised, contacts 1' 2' made, and his own machine has registered at the central register. In like manner it will be seen that the key at machine No. 2 will cut out the key at machine No. 3, and so on.

Having thus described my invention, I claim—

40 1. In a cash-register system, the combination of a series of groups of keys of different values, a single register at a distant point, and connecting mechanism, whereby upon the simultaneous operation of one or more keys in each group their full value will always be added on said register.

45 2. In a cash-register system, the combination of a series of groups of keys of different values, a single register at a distant point, and connecting mechanism, whereby upon the simultaneous operation at any time of two or more keys in the same group their full value will be added on said register.

50 3. In a cash-register system, the combination of series of machines, each having a series of keys and an indicator, a central register, and connecting mechanism adapted to transmit at all times unaltered to said central register the full value of any two or more simultaneously-operated keys of the system and to indicate the value of the keys on their respective machines.

55 4. In a cash-register system, a combination of a series of machines, each having a series of keys, a register, and an indicator, a central register, and connecting mechanism adapted to transmit to said central register the full

value of any two or more simultaneously-operated keys of the system and to indicate and register the value of the keys on their respective machines. 70

5. In a cash-register system, the combination of a central register, a machine having a series of keys, a register, and an indicator, and mechanism adapted to transmit from the machine to said central register the full value of an operated key and to transmit from said central register to the machine the same value. 75

6. In a cash-register system, a combination of a central register, a machine having a series of keys, an indicator, and a register, and mechanism adapted to transmit from the machine to the central register the full value of two or more simultaneously-operated keys and to transmit from said central register to 85 the register and indicator of the machine the same value. 80

7. In a cash-register system, the combination of a central register, a series of machines, each having a series of keys, an indicator, and a register, and mechanism adapted to transmit from said machines to said central register the full value of any two or more simultaneously-operated keys of the system and to transmit from said central register to 95 each individual machine the values of their respectively-operated keys. 90

8. In a cash-register system, the combination of a series of machines, each having a series of keys and a register, a central register 100 at a distant point, and mechanism adapted to transmit to said central register the full value of any operated key and for arresting said key for a brief interval of time just before the registration takes place. 105

9. In a cash-register system, the combination of a series of machines, each having a series of keys, a register, and an indicator, a central register, and mechanism whereby upon the simultaneous operation of any two keys they will be arrested in their motion, their full value will be transmitted to said central register, and their respective indicators reset. 110

10. In a cash-register, the combination of 115 a series of machines, each having a series of keys, a register, an indicator, and a cash-drawer, a central register, and mechanism whereby upon the operation of any keys of the system their full value will be transmitted 120 to said central register and will be added and indicated on their respective machines, and the drawers of each will be released.

11. In a cash-register system, the combination of a series of groups of keys of different 125 values, a central register, and mechanism whereby upon the simultaneous operation of two or more keys of the same value in the different groups only the key in a predetermined group will actuate said register. 130

12. In a cash-register system, the combination of a series of groups of keys of different values, a central register, and mechanism whereby upon the simultaneous operation of

several keys of the same value in the different groups only those in a predetermined group will actuate the central register.

13. In a cash-register system, a combination of a series of groups of keys of different values, a register connected therewith, and a cutting-out mechanism whereby upon the operation of two or more keys of the same value, but in different groups, all but one of said keys will be disconnected from said register.

14. In a cash-register system, the combination, of a central register, a series of machines, each having a series of keys, a register, and a bell, and mechanism whereby upon the simultaneous operation of two keys of the same value in different machines each key will actuate said central register and ring their bells in succession.

15. In a cash-register system, the combination of a central register, a series of machines, each having a drawer, and mechanism whereby said drawer is released only after the registration has taken place on said central register and on its individual machine.

16. In a cash-register system, the combination of a series of complete machines, a central register operated from any one of said machines, and an additional register at a distant point operated from said central register, substantially as described.

17. In a cash-register system, the combination, with a central register having its escapement-magnets arranged in parallel arc, of a local register, also having its escapement-magnets arranged in parallel arc, a bell and drawer-releasing magnets arranged in series, and means for successively energizing said escapement-magnets.

18. In a cash-register system, the combination of a central register and two or more local registers having their escapement-magnets all arranged in parallel arc, and contact-keys for actuating the escapements of the central

register from said local register, substantially as described.

45

19. In electric cash-register systems, the combination, with a central register, of a series of local cash-registers connected therewith in electric circuit, the keys of the local cash-registers constituting circuit-closers and adapted to transmit always to said central register their full value when simultaneously operated, substantially as described.

20. In electric cash-register systems, the central register, the local registering-machines connected in circuit therewith and having the circuit-closing keys, the electric locking device, and the electrically-operated shunt-switches to operate the locking device and hence prevent the drawer of the local machine from being opened until after registration takes place, substantially as described.

21. In an electric cash-register, the combination of the prime-moving gear, the escapement to release it, the finger-key, and connected electro-magnet to operate the escapement, and the electric locking device for the drawer, connected in shunt-circuit with the escapement, substantially as described.

22. In a cash-register system, the combination of one or more local registers and indicators and a central register connected to and operating said local registers and indicators.

23. In an electric cash-register system, the combination of one or more local cash registers and indicators and a central register electrically connected therewith and adapted to be operated from said local registers and indicators and to operate said local registers and indicators from itself.

75

In testimony that I claim the foregoing I append my signature.
